UNITED STATES PATENT OFFICE

JOHN G. H. LIEBEL AND EDWIN S. FLARSHEIM, OF CINCINNATI, OHIO, ASSIGNEES TO
THE LIEBEL-FLARSHEIM COMPANY, OF CINCINNATI, OHIO, A CORPORATION OF
OHIO

DESIGN FOR AN ARC LAMP HOOD

Application filed July 21, 1931. Serial No. 40,617. Term of patent 14 years.

To all whom it may concern:

Be it known that we, JOHN G. H. LIEBEL and EDWIN S. FLARSHEIM, both citizens of the United States, and both residents of Cincinnati, in the county of Hamilton, State of Ohio, have invented a new, original, and ornamental Design for an Arc Lamp Hood, of which the following is a specification, reference being had to the accompanying drawing, forming a part thereof.

The figure is a perspective view of the

front and one side of an arc lamp showing our new design.

The figure, being in perspective, shows the front and only one side. The opposite or left side, however, is substantially the same in appearance.

We claim:

The ornamental design for an arc lamp hood as shown and described.

JOHN G. H. LIEBEL.
EDWIN S. FLARSHEIM.
